UNITED STATES PATENT OFFICE

2,428,075

POLE CLIMBING HARNESS

James E. Hare, Uniontown, Pa.

Application May 10, 1946, Serial No. 668,894

1 Claim. (Cl. 227—24)

1

This invention relates to a pole climbing harness which is especially adapted for use in climbing circular poles, such as flagpoles, telegraph poles, lampposts and similar items.

An object of the invention is to provide a device that is simple in construction, efficient in operation, durable in use and inexpensive to manufacture.

Another object of the invention is to provide a device that is useful in painting flag poles or similar items.

With the above and other objects and advantages in view the invention consists of the novel details of construction, arrangement and combination of parts more fully hereinafter described, claimed and illustrated in the accompanying drawing in which:

Figure 1 is a perspective view of the leg harness;

Figure 2 is a perspective view of the foot harness;

Figure 3 is a view showing a person using the embodiment of the invention in climbing a pole and

Figure 4 is the clove hitch knot used with the harness in climbing the pole.

Referring to the drawing in detail and more especially to Figure 1 the numeral 10 designates the thigh band which is made of leather or similar material to which is attached by means of bifurcated ends 12 the supporting strap 14. The ends 12 are secured to the band 10 by rivets 15 or the like which also secure the thigh attaching straps 16 and 18 respectively. Strap 16 being provided with openings 20 to be engaged by the tongue 22 of the buckle 24 attached to the end of strap 18 whereby the band 10 is securely attached to the thigh of the user. A ring 26 on the strap 14 is adapted to receive one end of the supporting rope 28 which is attached to the pole 30 at the other end by a clove hitch 32.

In Figure 2 the foot supporting plate 34 which is shaped to substantially conform to the shape of a shoe is provided with a semispherical shaped notch 36 in the toe end thereof which is provided with a non-slipping material 38. The plate 34 will engage the pole 30 through the medium of the notch 36 to support the user's foot on the pole. Adjacent the heel portion of the plate 34 is provided the heel catch block 40 which engaging in the instep of the shoe of the wearer prevents the plate 34 from slipping from the wearer's foot. A supporting rope 42 provided with an eye 44 is looped under the plate 34 and retained thereon by a hanger 46 and a shoe attaching strap 48 inserted in opening 50 in the plate 34 is provided on one end with openings 52 to be engaged by the tongue 54 of the buckle 56 attached to

2

the other end. The rope 42 is also attached to the pole 30 by a clove hitch 32 as was the rope 28 and thus the plate is supported on the pole.

In use place the thigh harness on the right leg, and the foot harness on the left foot, attach the ropes by clove hitches to the pole. Push leg harness clove hitch up the pole as far as possible and tighten, shift weight to leg harness, push foot harness clove hitch up the pole as far as possible and tighten, shift weight on to foot harness and lift body into standing position by repeating the above described steps, a pole may be easily and quickly ascended. Descent is obtained by repeating these steps in reverse order.

It is believed that the operation and construction of the invention will be apparent to those skilled in the art and it is to be understood that changes in the details of construction, arrangement and combination of parts may be resorted to providing they fall within the spirit of the invention and the scope of the appended claim.

Having thus described the invention what is claimed as new and desired to be secured by Letters Patent is:

25 A device of the character described comprising a pole climbing harness having a thigh band, a supporting strap secured to the ends of said band, thigh attaching straps secured to said band inwardly of said supporting straps, a ring on said 30 supporting straps, a supporting rope engageable with said ring and a foot supporting plate which is shaped to conform to the shape of a shoe, a semi-spherical shaped notch in one end of said plate, a non-slipping material lining said notch, 35 adapted to engage the pole, a heel catch block adjacent the opposite end of said plate to prevent the shoe supported thereby from slipping therefrom, a foot engaging strap carried by said plate intermediate said notched end and said 40 block, a supporting rope carried by said plate, said thigh band and said plate adapted to support a pole climber on said pole when said supporting ropes are secured to said pole by clove hitch.
